INTERNAL KEYWAY GRINDER

Guy B. Carroll, Minneapolis, Minn.

Application July 7, 1941, Serial No. 401,316

32 Claims. (CL 51—92)

My invention relates to improvements in grinders and more particularly to a grinder for grinding internal keyways, internal gears and the like.

While the invention is intended for general use, it is especially well adapted for grinding internal keyways in the cylindrical barrel of a hydraulic pump as used by the Navy for gun control.

It is well known that these pump barrels are first made undersize, then hardened, which results in warpage, and thereafter finished to given dimensions. The pump barrel has an axial bore for a pump shaft that extends axially and loosely therethrough. The pump shaft is provided with two diametrically opposite keys that are fitted in keyways in the pump barrel and it is such keyways that we have to consider in the present application.

It is well known that at present internal keyways in a pump barrel are individually finished by hand to fit the keys on a particular pump shaft, which is a tedious and expensive operation. Each pump barrel and its shaft have marked thereon like identifying characters so that, when separated, they can be reassembled with the keys on a pump shaft in the keyways of a pump barrel finished therefor. The keys on no two pump shafts will fit the internal keyways in a given pump barrel and hence are not interchangeable.

The object of this invention is to grind internal keyways and the like to predetermined sizes.

Another object of this invention is to grind internal keyways in pump barrels to predetermined sizes and all exactly alike and hence interchangeable, and with their center lines concentric with the pump barrels.

Other objects of the invention will be apparent from the following description, reference being had to the accompanying drawings.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in front elevation and partly in section showing the invention mounted on a machine of the type of a surface grinder and also showing a pump barrel mounted on said machine;

Fig. 2 is a fragmentary view of the left-hand

portion of the machine, on an enlarged scale, and also showing the pump barrel and the means for mounting the same thereon, and the means for aligning the same;

5 Fig. 3 is a plan view of the parts shown in Fig. 2;

Fig. 4 is an end view of the parts shown in Fig. 2;

Fig. 5 is a view partly in side elevation and partly in section taken on the line 5—5 of Fig. 4;

10 Fig. 6 is a view of V aligning block in transverse vertical section;

Fig. 7 is a fragmentary view showing a modification of the pump barrel aligning device;

15 Fig. 8 is a plan view of the grinder, some parts being broken away;

Fig. 9 is a fragmentary view principally in horizontal section taken on the line 9—9 of Fig. 11;

20 Fig. 10 is a fragmentary view principally in section taken on the line 10—10 of Fig. 11;

Fig. 11 is a view of the grinding unit partly in side elevation and partly in longitudinal central vertical section;

25 Fig. 12 is a view of the control head removed from the grinder, some parts being broken away and sectioned;

Fig. 13 is a detail view partly in elevation and partly in section taken on the line 13—13 of

30 Fig. 8;

Fig. 14 is a view principally in end elevation with some parts sectioned on the line 14—14 of Fig. 11 and with other parts broken away;

Fig. 15 is a view principally in section taken on the line 15—15 of Fig. 11;

Fig. 16 is a fragmentary detail view partly in side elevation and partly in section taken on the line 16—16 of Fig. 8;

Fig. 17 is a front end elevation of the control head, some parts being broken away and other parts being sectioned;

Fig. 18 is a detail view partly in elevation and partly in section taken on the line 18—18 of Fig. 9;

45 Fig. 19 is a view in front elevation, on an enlarged scale, of one of the driving belt tighteners and directional pulleys and a section of the belt, shown by means of broken lines; and

Fig. 20 is a detail view partly in plan and partly in section taken on the line 20—20 of Fig. 15.

The invention is mounted on a machine of the type of a surface grinder and of the parts thereof, it is important to note the base or bed 21, on which a table 22 is mounted in ways 23 to be reciprocated endwise hydraulically, as indicated

55

at 24; the slide 25, mounted in ways 26 at the back of the machine for vertical movement; the screw 27 and a co-operating nut, not shown; and the connections for operating the nut including a hand wheel 28. In the top of the table 22 are the customary parallel T-slots 29 that extend longitudinally thereof.

The improved grinder includes a horizontally disposed cylindrical housing 30 having an integral supporting bracket 31 rigidly bolted to the side 25 on the face thereof. This housing 30 is open at both ends and its longitudinal axis is parallel to the upper face of the table 22. A cylindrical control head 32 is rotatably mounted in the housing 30 with a close working fit and with its axis coincident with the axis of said housing. This control head 32 is held against movement in the housing 30 by an annular flange 33 on one end thereof, and a nut 34 on the other end of said head. Said flange 33 and nut 34 impinge against the ends of the housing 30 as bases of resistance.

The control head 32 is rotated in the housing 30 one hundred eighty degrees, by a vertically movable rack 35 and co-operating gear teeth 36 in the control head 32 at the longitudinal center thereof. This rack 35 works endwise in a passageway 37 therefor in the housing 30. A stop member 38 on the flange 33 of the control head 32 and a pair of co-operating stop lugs 39 on the housing 30 limit the rotary movement of the control head 32 and permit a rotary movement thereof of exactly one hundred eighty degrees. The rack 35 is endwise reciprocated hydraulically by a pair of cylinders 40 and co-operating pistons, only the rods 41 of which are shown. These cylinders 40 are secured to the slide 25 below the table 22. By reference to Fig. 14 it will be noted that the rack 35, at its lower end, is connected to one of the piston rods 41 and a rod 42 connects the two piston rods 41, the one to the other. Formed in the control head 32 is a relatively large passageway 43 that is square in cross-section and extends completely through said head. The sides of the passageway 43 are the same distance from the axis of the control head 32.

Mounted in the control head 32 is a long control box that is square in cross-section and the ends thereof project outwardly of the ends of the control head 32. On the right-hand end of the control box 44 is a control disk 45 that extends transversely of said box. The control box 44 is free for horizontal adjustment relative to the control head 32 and has sliding contact with the upper and lower surfaces of said control box in the passageway 43. Oblique keys and co-operating keyways 46 in the contacting surface of the control head 32 and the control box 44 are provided for imparting lateral movement in a horizontal plane to said control box in the control head 32.

A second control box 47 is mounted in the control box 44 for vertical adjustment and has sliding contact with the vertical internal walls of the control box 44. Oblique keys and co-operating keyways 48 in the contacting surfaces of the control boxes 44 and 47 are provided for imparting vertical movement to the control box 47 in the control box 44. The control box 47 extends outwardly of the ends of the control box 44, and formed with the right-hand end of the control box 47 is a control disk 49 that extends transversely thereof. Both control boxes 44 and 47 are open at their ends and the in-

terior of the control box 47 is round in cross-section.

Mounted in the control box 47 is a long tubular shaft 50 held by a key 50' against rotation therein. On the right-hand end of the shaft 50 is an annular flange 51 that engages the control box 47 at its respective end, and a nut 52 on the shaft 50 engages the other end of said box. The flange 51 and nut 52 hold the shaft 50 against axial movement in the control box 47. The shaft 50 outwardly of the control box 47 and the nut 52 is reduced in diameter and extends materially to the left from the control box 47 and this section or extension of the shaft 50 is designated by the numeral 53. In the actual usage of the improved grinder, the same will be provided with a plurality of shafts 50 of the same diameter to fit the passageways therefor in the control box 47, but having extensions 53 of different diameters for different types and sizes of work.

A grinding wheel 54 is mounted on the outer end portion of the shaft extension 53, which is cut away as indicated at 55, to afford clearance for said wheel. Formed with the internal wall of the shaft extension 53 is a stub shaft 56 that extends diametrically and horizontally therethrough. The grinding wheel 54 is mounted on a relatively large tubular hub 57 and is clamped thereon between a flange 58 integral with said hub and a loose flange and a nut 59, the latter having screw-threaded engagement with the hub 57. The hub 57 extends axially over the shaft 56 and is mounted thereon by ball bearing assembly 60 interposed therebetween. A washer 61, secured to the outer end of the shaft extension 53 by a machine screw 62, holds the ball bearing assembly 60 and the hub 57 on the shaft 56. The inner end portion of the hub 57, that extends inwardly from the flange 58, affords a pulley 63. It will be noted that the projected longitudinal axes of the shaft 50 and its extension 53 extend diametrically through the grinding wheel 54 relatively close to the inner face thereof. The axis about which the grinding wheel 54 rotates is coincident with the longitudinal axis of the shaft extension 53 and perpendicular thereto. A plate 64 affords a closure for the outer end portion of the shaft extension 53 and is removably secured thereto by a suitable clamping device, not shown.

The grinding wheel 54 is driven by a belt 65 from an electric motor 66. The belt 65 is flat but, of course, may be a V belt. This motor 66 is mounted on a bracket 67 rigidly secured to the right-hand end of the tubular shaft 50. A pulley 68, encircling the motor 66, is keyed to the armature shaft thereof and aligned with the pulley 63. The pulley 68 is relatively large in respect to the pulley 63 and the belt 65 runs over said two pulleys and longitudinally through the shaft 50 and its extension 53. The belt 65, at the right-hand end of the shaft 50, runs over two rolls 69 that act as belt tighteners and directional rolls for said belt. These rolls 69 are journaled in adjustable bearing brackets 70 secured to the control disk 49 by machine screws 71 that extend through slots 72 in said bracket.

The grinding wheel 54 and the electric motor 66 and their associated elements are substantially balanced about the longitudinal axis of the shaft 50 and its extension 53. The grinding wheel 54 rotates in a plane parallel to the projected axis of the control head 32 and by moving the control box 44 laterally in said head, the

grinding wheel 54 is moved laterally toward or from said axis. To move the control box 44 laterally by sliding the same obliquely in the control head 32 by means of the keys and co-operating keyways 48, the following automatic and manually controlled connections are provided, to wit: a long screw shaft 73 that extends parallel to the axis of the control head 32 is turnably mounted in a right-hand bearing 74 and a bifurcated left-hand bearing 75 on the housing 30. Integral with the left-hand end of the shaft 73 is a pair of jaws 76 between which the control disk 45 extends and is held thereby against lateral movement, but is free for edgewise movement therebetween. The manual connections for moving the screw shaft 73 endwise includes a nut-acting bevel gear 77 on the screw-threaded end portion of the shaft 73 to the left of the bearing 75. A bevel gear 78 meshing with the bevel gear 77 is rigidly secured to the inner end of a shaft 79 that extends perpendicular to the shaft 73. The shaft 79 is journaled in an outer and an inner bearing 80 on the housing 30 and has on its outer end a hand wheel 81 by which said shaft may be turned.

The automatic connections for moving the screw shaft 73 endwise includes a nut-acting ratchet wheel 82 held between the prongs of the bearing 75 against axial movement on said shaft. A step of rotary movement is imparted to the ratchet wheel 82, at the limit of the endwise movement of the rack 35 when rotating the control head 32, by a spring-pressed pawl 83 on a pawl carrier 84. This pawl carrier 84 is bifurcated and straddles the pawl 83 and the prongs thereof are pivoted to the shaft 73 between the prongs of the bearing 75. The pawl carrier 84 is yieldingly held on a vertically adjustable stop pin 85, having screw-threaded engagement with the housing 30, by a coiled spring 86 attached to said carrier and anchored to the housing 30. The pawl carrier 84 is lifted from the stop pin 85, to impart a step of rotary movement to the ratchet wheel 82 by means of the pawl 83, by a laterally projected lug 87 on the lower end portion of the rack 35.

To move the control box 47 vertically, by sliding the same obliquely in the control box 44 by means of the keys and keyways 48, the following automatic connections are provided, to wit: a long square bar 88, extending parallel to the axis of the control head 32, is slidably mounted in a way 89 on the underside of the housing 30 and held therein by transverse plates 90. A pair of jaws 91, integral with the right-hand end of the bar 88, engages the control disk 45 on opposite sides thereof and thereby holds said disk against lateral movement but permits free edgewise movement of the disk 45 therebetween. The bar 88 is endwise reciprocated, to successively raise and lower control box 47 and hence the grinding wheel 54 by hydraulic means including a pair of cylinders 92 and co-operating pistons, only the rods 93 of which are shown. The cylinders 92 are mounted on the slide 25. One of the piston rods 93 is secured to the bar 88 by a lug 94 integral therewith, and a rod 95 connects the other piston rod 93 to said lug.

Adjustable inner and outer stops 96 and 97, respectively, are provided for limiting the raising and lowering movements of the control box 47 and hence the grinding wheel 54. These stops 96 and 97 are in the form of depending jaws on the left-hand of a pair of bars 98 and 99, respectively, and between which jaws the control

disk 45 extends. The bars 98 and 99 are slidably mounted, the latter on the former and both thereof are mounted in a way 100 in the top of the housing 30 for endwise sliding movement parallel to the axis of the control head 32. Opening and closing movements are imparted to the stop jaws 96 and 97 by means of a pair of keys 101 in the form of an X, that work in co-operating ways 102 in the bars 98 and 99. These keys 101 are carried by a spider 103 having a cylindrical body 104 which extends transversely of the bars 98 and 99. A long screw shaft 105 extends axially and loosely through the body 104 and said body is held against axial movement on the shaft 105 by a pair of collars 106 rigidly secured to said shaft at the ends of the body 104. The shaft 105 is mounted in a front bearing 107 and a rear bifurcated bearing 108 on the housing 30. The housing 30 is flattened at 109 to afford clearance for the keys 103. On the front end of the shaft 105 is a hand wheel 105' by which the described connections may be manually operated to open the stops 96 and 97.

The stop jaws 96 and 97 are progressively and automatically opened by a nut-acting ratchet wheel 110 having screw-threaded engagement with the screw shaft 105 between the prongs of the bearing 108. A step of rotary movement is imparted to the ratchet wheel 110, simultaneously with that of the ratchet wheel 82 at the limit of the endwise movement of the rack 35 when rotating the control head 32, by a spring-pressed pawl 111 on a pawl carrier 112. This pawl carrier 112 is bifurcated, straddles the ratchet wheel 82 and the prongs thereof are pivoted on the shaft 105 between the prongs of the bearing 108. The pawl carrier 112 is yieldingly held on a vertically adjustable stop pin 113 having screw-threaded engagement with the housing 30, by a coiled spring 114 attached to said carrier and anchored to the housing 30. The pawl carrier 112 is lifted from the stop pin 85 to impart a step of movement to the ratchet wheel 110, by a laterally projecting lug 115 on the lower end portion of the rack 35. While the shaft 105 is being moved endwise to automatically open the stop jaws 96 and 97, said shaft is held against rotation by clamping the divided bearing 107 thereon. By reference to Fig. 14, it will be noted that the bearing 107 is divided at one side of the shaft 105 and provided with a nut-equipped bolt 116 for contracting said bearing on the shaft 105.

A hydraulic pump barrel 117 of the type used by the navy for gun control is mounted in a V-block 118 on the left-hand end of the table 22. As shown, the table 22 has three T-slots 29 and the V-block 118 has on its bottom at its transverse center a key 119 slidably mounted in the central T-slot 29 and aligns said block with the table 22. This V-block 118 is rigidly secured to the table 22 by nut-equipped bolts 120 anchored in the two outer T-slots 29 and extends through transverse slots 121 in the base of said block. The pump barrel 117 is rigidly clamped in the V-block 118 by a flat metal band 122 that extends transversely over said barrel. This band 122 has on its end portions screw stud extensions 123 that extend through apertures in the V-block 118 and have nuts and washers 124 applied to the lower ends thereof that engage the V-block 118 as a base of resistance.

The pump barrel 117, shown in Figs. 2 to 6, inclusive, has an intermediate axial bore 125 for a pump shaft, not shown, and also has a counter-bore 126 in each end. This pump barrel 117 also

has upper and lower keyways 127 at its bore 125 that extend into the counterbores 126. The diameter of the counterbores 126 is somewhat greater than the distance between the bottom of the two keyways 127. In the face of the pump barrel 117 is a plurality of circumferentially spaced cylinders 128. These cylinders 128 open into ports 129 in the back of the pump barrel 117. It will be noted that the distance between the cylinders 128 is not all the same, but a line extending between the longitudinal axes of the two lowermost diametrically opposite cylinders 128 is perpendicular to a vertical plane passing through the longitudinal axis of the bores 125 and the transverse centers of the two keyways 127. These two cylinders 128 are further identified by the letter A.

To align the pump barrel 117 with its longitudinal axis and the transverse centers of the keyways 127 in the same vertical plane and with the axes of the two cylinders A in a horizontal plane, the following devices are provided: A pair of snugly fitted pins 130 are inserted part way into the two cylinders A and a co-operating vertically disposed bar 131 is slidably mounted in upper and lower keeper brackets 132 on the left-hand end of the bed 21 and has on its upper end a crosshead 133, the upper edge of which is horizontal. In aligning the pump barrel 117, the table 22 is operated to position said barrel with the pins 130 projecting transversely over the crosshead 133 and the bar 131 is raised to engage its crosshead 133 with the pins 130, and the pump barrel 117 is turned about its axis in the V-block until both of the pins 130 engage the crosshead 133. The nuts 120 are then tightened to clamp the band 122 onto the pump barrel 117 to rigidly secure the same in the V-block 118. With the pump cylinder 117 thus secured to the table 22, its axis is in the same vertical plane with the longitudinal axis of the control head 32. Next the slide 25 is vertically adjusted by manipulating the hand wheel 28 to bring the longitudinal axis of the control head 32 into alignment with the longitudinal axis of the pump barrel 117.

In certain other pump barrels the spacing of the cylinders is such that it is necessary to use two of said cylinders in a pump barrel that are vertically spaced, as shown in Fig. 7. In this figure, the pump barrel and all parts thereof as well as the positioning pins, the bar and its crosshead are given the same reference numerals and letters as are used in Figs. 2 to 6, inclusive, except that a prime has been placed thereafter. The bar 131' is mounted for horizontal sliding movement in guides 134 on a bracket 135 secured to the bed 21.

Obviously, the control head 32 and the control boxes 44 and 47 afford a control unit for turning the grinding wheel 54 face for face about the longitudinal axis of the shaft extension 53 and positioning the same in a vertical plane on either side thereof, for adjusting the grinding wheel 54 laterally in respect to the projected longitudinal axis of the control head 32, and for raising and lowering the grinding wheel 54 in respect to said projected axis.

It is also obvious that the ratchet wheel 82, with the manually operated connections thereto from the hand wheel 81, or the automatic connections thereto from the rack 35, and the connections from said ratchet wheel to the control disk 46 afford a feed for moving the grinding wheel 54 laterally to its work. The stops 86 and 87, which may be manually set by means of the

connections from the hand wheel 81, automatically feed the grinding wheel 54 in the plane thereof to its work. The width of the grinding wheel 54 is such as to grind a little more than one-half of the width of the keyways 127 so that the cuts made by the grinding wheel 54 at the center of the keyways overlap.

Operation

10 The operation of the improved grinder may be briefly described as follows: The table 22 is hydraulically reciprocated, as indicated at 24, in the well known manner, first to project the shaft extension 53 through the bore 125 in the pump barrel 117 and then retract the same. The sides of the keyways 127 are successively ground by the outer face of the grinding wheel 54 and the bottoms of said keyways are ground by the periphery thereof. The control box 47, which raises and lowers the grinding wheel 54, and the rack 35, which turns the grinding wheel 54 one hundred eighty (180°) degrees and thereby reverses the same face for face, are both hydraulically operated and the movements thereof are synchronized with the movement of the hydraulically reciprocated table 22. Lateral and peripheral feeding movements are imparted to the grinding wheel 54 by the rack 35 at the limit of its upward movement when turning the control head 32.

15 It may be assumed that the rack 35 is in its lowermost position and is holding the control head 32 with its stop member 38 against one of the stop lugs 39, and that the control boxes 44 and 47, the shaft 50 and its extension 53 are all in central positions or, in other words, their axes are co-incident with the axis of the control head 32. As heretofore stated, the keyways 127 primarily are undersize and must be ground to a predetermined width and a predetermined depth.

20 The first step in the operation of my grinder is to manipulate the hand wheel 81 manually to move the control box 44 laterally, by means of the keys and keyways 46, to position the grinding wheel 54 to grind with its outer face say, the left-hand side of the lower keyway 129, and the control box 47 is hydraulically operated and lowered by means of the keys and keyways 48 to position the grinding wheel 54 to grind with its periphery the left-hand one-half of the lower keyway 127 and to position the control box 47 with its control disk 49 against the stop 96. The table 22 is then hydraulically operated to project the shaft extension 53 through the bore 127 in the pump barrel 117 and thereby feed the grinding wheel 54 to its work.

25 The second step in the operation of the grinder is to hydraulically operate the control box 47, when the grinding wheel 54 is out of the pump barrel 117, to lift the same, by means of the keys and keyways 48, and position the grinding wheel 54 to grind with its outer face the left-hand side of the upper keyway 127 and at the same time to grind with its periphery the adjacent one-half of the bottom of said upper keyway. The distance the control box 47 is raised is determined by the movement of the control disk 45 from the stop 96 to the stop 97. This lifting movement of the control box 47 positions the grinding wheel 54, with the uppermost surface of its periphery exactly the same distance above a horizontal plane, extending from the longitudinal axis of the pump barrel 117, as the lowermost surface of said periphery was below said plane. With the grinding wheel 54 in its raised position, the table 22 is again hydraulically operated to retract the shaft

extension 53 and thereby feed the grinding wheel 54 to its work.

The third step in the grinding operation is, after the grinding wheel 54 has been completely withdrawn from this pump barrel 117 during its retracting movement, to hydraulically raise the rack 35 and thereby turn the control head 32 and all parts carried thereby one hundred eighty degrees (180°), and position the grinding wheel 54 on the other side of the longitudinal axis of the shaft extension 53 and with its outer face, by which the sides of the keyways 125 are ground, exactly the same distance from said axis as when the other side thereof, plus a lateral feeding imparted to the grinding wheel 54 by the ratchet wheel 82 and associated parts, which took place at the limit of the upward movement of the rack 35 when its trip lug 87 lifted the pawl carrier 84 and operated the ratchet wheel 82. This rotation of the control head 43 positions the grinding wheel 54 to grind the right-hand side and the adjacent one-half of the upper keyway 125. The table 22 is now again hydraulically operated to project the shaft extension 53 through the bore 125 in the pump barrel 117 and feed the grinding wheel 54 to its work. At the same time that the ratchet wheel 82 is indirectly operated by the rack 35 to feed the grinding wheel 54 laterally, the stops 96 and 97 are separated, a step of movement by the ratchet wheel 110 actuated by the trip lug 115 on the rack 35 while lifting the pawl carrier 112, to permit an increased movement of the control box 47 and thereby feed the grinding wheel 54 in the plane thereof to increase the depth of cut made thereby.

The fourth and final step in the operation of the grinder is, after the grinding wheel 54 has been moved out of the pump barrel 117, to hydraulically operate the control box 47 and lower the same until its control disk 49 engages the stop 96 and thereby positions the grinding wheel 54 to grind the right-hand side of the keyway 125, the adjacent one-half of its bottom. The table 22 is now again operated to retract the shaft extension 53, through the bore 125 in the pump barrel 117, and feed the grinding wheel 54 to its work. When the grinding wheel is retracted completely out of the pump barrel 117, the rack 35 is drawing downwardly hydraulically and rotates the control head 32 and parts associated therewith one hundred eighty degrees (180°), and returns the grinding wheels 54 to its starting position and completes a cycle of operation of the grinder. Obviously, each time the rack 35 is hydraulically moved upwardly to rotate the control head 32, the grinding wheel 54 is fed a step of movement both axially and in the plane thereof.

After the grinding wheel 54 is manually positioned to first grind the left-hand side of the lower keyway 127 and the adjacent one-half of the bottom thereof, it may take one or more cycles of operation of the grinder before grinding action actually takes place. It is, of course, evident that the grinding cuts made by the outer face and periphery of the grinding wheel 54 are very slight.

From the foregoing, it is evident that the invention herein disclosed and claimed is capable of a large range of modification within the spirit of the invention.

What I claim is:

1. The combination with a support, of a grinding unit including a shaft mounted on the support, a grinding wheel journaled on the shaft,

an electric motor mounted on the shaft, driving connections from the motor to the grinding wheel, means for adjusting the grinding unit to periodically and successively raise and lower the grinding wheel to feed the same in the plane thereof to its work, and other means for periodically and progressively increasing the distance the grinding wheel is raised and lowered by the grinding unit relative to the work.

10 2. The combination with a support, of a grinding unit including a shaft mounted on the support, a grinding wheel journaled on the shaft, an electric motor mounted on the shaft, driving connections from the motor to the grinding wheel, means for adjusting the grinding unit to periodically and successively raise and lower the grinding wheel to feed the same in the plane thereof to its work, and other automatic means for periodically and progressively increasing the distance the grinding wheel is raised and lowered by the grinding unit relative to the work.

15 3. The combination with a support, of a grinding unit including a shaft mounted on the support, a grinding wheel journaled on the shaft, an electric motor mounted on the shaft, driving connections from the motor to the grinding wheel, means for adjusting the grinding unit to feed the grinding wheel laterally to its work, and other means for rotating the shaft to successively turn the grinding wheel face for face.

20 4. The combination with a support of a grinding unit mounted on the support including a shaft, a rotatable grinding wheel journaled on the shaft for rotation in a plane parallel thereto, the inner face of the grinding wheel being substantially at the axis of the shaft, means for rotating the grinding wheel, and means for rotating the shaft to turn the grinding wheel face for face.

25 5. The combination with a support of a grinding unit mounted on the support including a rotatable control head, outer and inner control boxes, a shaft carried by the inner control box, a grinding wheel journaled on the shaft in a plane parallel thereto, means for rotating the grinding wheel, means for periodically rotating the control head and then reversing the same to turn the grinding wheel face for face, said outer control box being mounted in the control head for movement relative thereto to move the grinding wheel laterally, said inner control box being mounted in the outer control box for movement relative thereto, to raise and lower the grinding wheel in the plane thereof, and separate and independent means for moving the outer control box in the control head and the inner control box in the outer control box.

30 6. The structure defined in claim 5 which further includes separate and independent means for guiding the outer control box obliquely in the control head and the inner control box obliquely in the outer control box.

35 7. The structure defined in claim 5 which further includes automatic means for moving the outer control box in the control head to periodically and progressively feed the grinding wheel laterally to its work.

40 8. The structure defined in claim 5 which further includes automatic means for periodically and progressively increasing the distance the inner control box is raised and lowered to feed the grinding wheel in the plane thereof to its work.

45 9. The combination with a support, of a grinding unit mounted on the support including a rotatable control head, outer and inner control

- boxes, and a shaft carried by the inner control box, a grinding wheel journaled on the shaft for rotation in a plane parallel thereto, means for rotating the grinding wheel, means for periodically rotating the control head and then reversing the same to turn the grinding wheel face for face, including a segment of a ring gear on the control head and a co-operating rack, said outer control box being mounted in the control head for movement relative thereto, to move the grinding wheel laterally, said inner control box being mounted in the outer control box for movement relative thereto, to raise and lower the grinding wheel in the plane thereof, and separate and independent means for moving the outer control box in the control head and for moving the inner control box in the outer control box. 15
10. The structure defined in claim 9 which further includes automatic means for periodically and progressively moving the outer control box in the control head to feed the grinding wheel laterally to its work.
11. The structure defined in claim 9 which further includes automatic means actuated by the rack for periodically and progressively moving the outer control box in the control head to feed the grinding wheel laterally to its work. 25
12. The structure defined in claim 9 which further includes movable stops for limiting the raising and lowering movements of the inner control head, and automatic means for periodically and progressively adjusting the stops to increase feed of the grinding wheel in the plane thereof to its work.
13. The structure defined in claim 9 which further includes movable stops for limiting the raising and lowering movements of the inner control head, and automatic means actuated by the rack for periodically and progressively adjusting the stops to increase feed of the grinding wheel in the plane thereof to its work. 35
14. The structure defined in claim 9 which further includes separate and independent means for guiding the outer control box obliquely in the control head and the inner control box obliquely in the outer control box.
15. The structure defined in claim 9 in which the longitudinal axis of the shaft is aligned with the corresponding axis of the inner control head and in which the control heads are primarily positioned with their longitudinal axis coincident with the longitudinal axis of the control head. 40
16. The combination with a support, of a grinding unit mounted on the support including a rotatable control head, outer and inner control boxes each having a control disk, a shaft carried by the inner control box, a grinding wheel journaled on the shaft with its axis perpendicular to the longitudinal axis of said shaft, means for rotating the grinding wheel and reversing the same to turn the grinding wheel face for face including a segment of a ring gear on the control head and a co-operating rack, said outer control box being mounted in the control head for movement relative thereto, to move the grinding wheel laterally, said inner control box being mounted in the outer control box for movement relative thereto, to raise and lower the grinding wheel in the plane thereof, separate and independent means including jaws for moving the outer control box in the control head and the inner control box in the outer control box, said jaws holding the control disks against axial movements but permitting relative edgewise movements thereof, means including a pair of 70
- stop jaws between which the control disk on the inner control box extends for limiting the raising and lowering movements of the inner control box in the outer control box. 45
5. 17. The structure defined in claim 16 which further includes automatic means actuated by the rack for periodically and progressively moving the outer control box in the control head to feed the grinding wheel laterally to its work.
10. 18. The structure defined in claim 16 which further includes automatic means actuated by the rack for periodically and progressively separating the stop jaws to increase the feed of the grinding wheel in the plane thereof to its work. 50
15. 19. The combination with a support, of a grinding unit mounted on the support including a rotatable control head, a shaft extending axially in the control head and held for rotation therewith, a grinding wheel journaled on the shaft in a plane parallel thereto, means for rotating the grinding wheel, and other means for periodically rotating the control head to turn the grinding wheel laterally and bodily about the axis of the shaft.
20. 20. The combination with a support, of a grinding unit mounted on the support including a rotatable control head, a shaft extending axially in the control head, a grinding wheel journaled on the shaft in a plane parallel thereto, means for rotating the grinding wheel, and other means for periodically rotating the control head to turn the grinding wheel laterally and bodily about the axis of the shaft. 55
25. 21. The combination with a support, of a grinding unit mounted on the support including a rotatable control head, a shaft extending axially in the control head, a grinding wheel journaled on the shaft in a plane parallel thereto, means for rotating the grinding wheel, and other means for periodically rotating the control head to turn the grinding wheel laterally and bodily about the axis of the shaft. 60
30. 22. The combination with a support, of a grinding unit mounted on the support including a rotatable control head, a shaft extending axially in the control head and held for rotation therewith, a grinding wheel journaled on the shaft in a plane parallel thereto, means for rotating the grinding wheel, and automatic means for mounting the shaft in the control head for rotation therewith and for relative adjustment to feed the grinding wheel laterally. 65
35. 23. The combination with a support, of a grinding unit mounted on the support including a rotatable control head, a shaft extending axially in the control head, held for rotation therewith but free for relative endwise reciprocating movement, a grinding wheel journaled on the shaft in a plane parallel thereto, means for rotating the grinding wheel, and automatic means for endwise reciprocating the shaft. 70
40. 24. The combination with a support, of a grinding unit mounted on the support including a rotatable control head, a shaft extending axially in the control head, a grinding wheel journaled on the shaft in a plane parallel thereto, means for rotating the grinding wheel, means for mounting the shaft on the control head for rotation therewith and for relative lateral adjustment, and automatic means for periodically and progressively adjusting the shaft mounting means to feed the grinding wheel laterally. 75
45. 25. The combination with a support, of a grinding unit mounted on the support including a rotatable control head, a shaft extending axially in the control head, a grinding wheel jour-

naled on the shaft in a plane parallel thereto, means for rotating the grinding wheel, means mounting the shaft in the control head for rotation therewith for relative transverse adjustment, and automatic means for periodically and progressively adjusting the shaft to feed the grinding wheel radially perpendicular to the axis of the control head.

26. The combination with a normally stationary support, of a rotatable grinding unit mounted on the support, a shaft extending axially through the grinding unit and held for common rotation therewith, a grinding wheel journaled on the shaft in a plane parallel thereto, an electric motor mounted on the shaft, driving connections from the motor to the grinding wheel, and means for moving the grinding unit relative to the support to adjust the shaft radially in a plane perpendicular to the plane of the grinding wheel to feed one face of the grinding wheel against a surface of a piece of work.

27. The combination with a normally stationary support, of a rotatable grinding unit mounted on the support, a shaft extending axially through the grinding unit and held for common rotation therewith, a grinding wheel journaled on the shaft in a plane parallel thereto, an electric motor mounted on the shaft, driving connections from the motor to the grinding wheel, and means for moving the grinding unit relative to the support to adjust the shaft radially in a plane parallel to the plane of the grinding wheel to successively position the periphery of the grinding wheel at diametrically opposite points transversely of the shaft against opposite surfaces of a piece of work.

28. The combination with a normally stationary support, of a rotatable grinding unit mounted on the support, a shaft extending axially through the grinding unit and held for common rotation therewith, a grinding wheel journaled on the shaft in a plane parallel thereto, an electric motor mounted on the shaft, driving connections from the motor to the grinding wheel, and means for moving the grinding unit relative to the support to adjust the shaft radially in a plane parallel to the plane of the grinding wheel to periodically and successively position the periphery of the grinding wheel at diametrically opposite points transversely of the shaft against opposite surfaces of a piece of work.

29. The combination with a normally stationary support, of a rotatable grinding unit mounted on the support, a shaft extending axially through the grinding unit and held for common rotation therewith, a grinding wheel journaled on the shaft in a plane parallel thereto, means for rotating the grinding unit in the support to turn the grinding wheel bodily laterally about the axis of the shaft to successively position its outer face on opposite sides of the axis of the shaft, and other means for adjusting the grinding unit laterally relative to the support in a plane perpendicular to the plane of the grinding wheel to feed the grinding wheel laterally against a surface of a piece of work.

30. The structure defined in claim 29 further including means for adjusting the grinding unit relative to the support in a plane parallel to the plane of the grinding wheel to successively position the periphery of the grinding wheel at diametrically opposite points transversely of the shaft against opposite surfaces of a piece of work.

31. The combination with a support, of a grinding unit mounted on the support including a rotatable control head, a tubular shaft extending axially through the control head and held for common rotation therewith, a grinding wheel journaled on the shaft at one end thereof, in a plane parallel thereto and having a driven pulley, an electric motor mounted on the shaft at the other end thereof, a driving pulley encircling the motor intermediate of its ends and secured to its armature shaft, a belt extending through the shaft and arranged to run over the two pulleys, the grinding wheel, the motor and their associated parts being substantially balanced about the longitudinal axis of the shaft, and compound means for adjusting the shaft radially in the control head in planes parallel with and perpendicular to the plane of the grinding wheel.

32. The combination with a normally stationary support, of a grinding unit including a control head rotatably mounted on the support, means for rotating the control head, a shaft extending axially through the control head and held for common rotation therewith, a grinding wheel journaled on the shaft in a plane parallel thereto, means for rotating the grinding wheel, and means for adjusting the shaft radially in the control head to feed the grinding wheel laterally.

GUY B. CARROLL.
